BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

DRILL.

1,104,989.

Specification of Letters Patent. Patented July 28, 1914.

Application filed January 15, 1914. Serial No. 812,264.

To all whom it may concern:

Be it known that I, BENGT M. W. HANSON, a citizen of the United States, residing at Hartford, in the county of Hartford and State of Connecticut, have invented certain new and useful Improvements in Drills, of which the following is a specification.

This invention relates to drills, one of the primary objects of the invention being the provision of an article of this character by which chips can be discharged with certainty and positiveness from the cutting zone. There are several advantages arising from this particular construction, one being 15 the facility and freeness with which the drill cuts and the other its rapidity of action as compared with those of the ordinary kind.

In the drawings accompanying and forming part of the present specification I have shown in detail one of the many different forms of embodiment of the invention, which to enable those skilled in the art to practice the same will be set forth fully in the following description. I do not limit myself 25 to this disclosure; I may depart therefrom in radical respects within the scope of the invention defined by my claims following said description.

Referring to said drawings: Figure 1 is a 30 top plan view of a drill embodying my invention. Fig. 2 is a side elevation of said drill. Fig. 3 is a bottom plan view of the same. Fig. 4 is a front elevation of said drill. Fig. 5 is a transverse section on the line 5—5 of Fig. 3, and, Fig. 6 is a rear elevation of the same.

Like characters refer to like parts throughout the several figures of the drawings.

The drill constituting the subject matter 40 of the present case has a plurality of cutting portions, and a chip-outlet common to the several cutting portions. There may be any desired number of these cutting-portions; in the form of the device shown there are 45 two. The chip-outlet may be of any convenient character; for instance it may consist of a flute of desired shape, such as a straight groove extending longitudinally of the drill. In conjunction with the drill there 50 is means whereby lubricant or some analogous substances, can be supplied to the cutting-zone, and while this lubricant or its equivalent can be furnished in any desirable manner, I prefer that the drill itself have

duct means for the conveyance thereof to 55 the cutting-zone, the lubricant which is generally supplied under pressure, being preferably utilized to expel the chips from said cutting-zone and force the same into and along the chip-outlet. The drill of ordinary 60 kind comprises as is known a plurality of lips, usually two, and a corresponding number of flutes which convey the chips away from the respective cutting-lips. There is an inherent disadvantage in this old form 65 of drill, as I will now explain. It has been the custom to utilize the pressure of the lubricating substance of whatever nature the same may be, to force the chips into and along the flutes of the old drill. They of 70 course are disposed therein at and around the lips. It is obvious that the resistance offered by the two masses of chips in the flutes is not the same, the consequence being that the lubricant will naturally take the 75 path of least resistance which will be along the flute containing that mass of chips which offers the less resistance to the onflowing lubricant, by reason of which one flute will be freed relatively speaking, of the chips 80 while the other will not and the chips continuing to pack therein, can be removed only by independent influence. By providing a drill of the novel kind set forth, the 85 disadvantage in question is not possible, for there is only one path for the chips to take and the lubricant must of necessity and imperatively force the chips along this path, so that clogging or choking by the chips of the single flute is practically impossible. 90 The chips may at times under unusual conditions, pack in and around the cutting-zone, but they must with certainty ultimately be expelled therefrom by the pressure of the lubricant. 95

I wish to make clear the fact that my invention consists in certain broad relations and not in any details, I having merely shown one of the numerous forms thereof in order to comply with the statutes, and which 100 I consider to be the best, after experiment.

With the foregoing general observations I will now refer more in detail to what is shown in the drawings. The drill comprises a shank denoted in a general way by 105 2. For facility of manufacture the shank is made up of a body member as 3, and a bit member as 4, the inner portion of the

bit member 4 being circumferentially reduced to cylindrical form as at 5 to closely fit a correspondingly-shaped socket as 6 at the forward end of the body member 3.

5 At the tip of the shank 2 is a wing or blade 7 formed by cutting away the stock at the forward end of the shank 2, this wing as will hereinafter appear carrying cutting lips which constitute suitable cutting portions 10 and which in the construction shown, are transverse to the chip-outlet or at least to the entering end thereof. As will herein-after appear the chip-outlet may consist of a straight flute or groove extending from the 15 base of said wing to practically the butt of the shank 2. The forward end of the wing 7 has angular surfaces 8 which converge to a comparatively blunt point intersected by the longitudinal axis of the drill, 20 The angular surfaces 8 have cutting portions as the edges 9 at opposite sides of the wing 7, and these cutting edges 9 radial to the longitudinal axis of the drill, present the lips proper. Each inclined surface 8 is on 25 a back taper to present a relief, further chip-clearance being provided by forming on the opposite surfaces of the wing 7 the relief portions 11. It should be noted that one side of the wing 7, that to the right in Fig. 2, 30 is flush with the uncut part of the shank 2. Attention is called to the fact that the wing is of progressively increasing thickness commencing at its top or crown, the thicker portion of the wing being at what might properly be considered the base thereof to thereby more effectually resist torsion and other effects present in work.

As shown the shank 2 has a straight flute or groove as 12 extending from practically 40 the butt or tang of the shank 3 uninterruptedly to the base of the wing 7, and this as already noted constitutes one of the several convenient chip-outlets. The sides of the wing 7 are upon rearwardly converging 45 angles as at 13 to provide for further relief. The rear portion of the wing 7 it will be seen, commencing at its top is upon a gentle curve as at 13' merging practically unbrokenly into the bottom of the forward 50 or inlet-portion of the outlet or duct 12. The shank 2 at opposite sides of the wing 7 has duplicate curved surfaces 14, the curves of which merge unbrokenly into the side curved faces of the wing 7 and also into the forward portion of the flute or groove 12. These surfaces 14 constitute guide portions 55 for initially directing the chips toward the flute or groove 12.

As the drill turns in a hole the oppositely-60 disposed lips 9 will cut and the chips pass onto the respective guide surfaces 14 from whence they are directed into the entering end of the flute or groove 12, this action being as already set forth a forced one and the lubricant which is utilized for lubricating

the area to be cut presenting a convenient means of effecting with certainty the discharge of the chips not only into but along the duct or groove 12, so that blocking or choking of the chips in the hole being cut 70 or in the chip-outlet is practically impossible. As I have already stated the lubricant or other chip-forcing substance can be conveyed to the cutting-portion of the drill in any desirable manner. I get the best results, however, by conducting it through the drill itself and will now describe one of the 75 many means whereby this particular function can be accomplished. Extending longitudinally of the shank 2 is a duct 15 which may be supplied at its outer open end with oil in any desirable manner for instance from the well-known oil pump generally an adjunct in metal-working machines. The major part of the duct 15 in the body member 3 is formed by channeling as at 16, the open outer side of the channel being closed by a cover-plate or strip 17 driven into place and held therein by beveled faces thereon adapted to engage correspondingly undercut beveled faces on the side walls of the channel 16. The duct 15 takes a slight dip beyond the forward end of the cover piece 17 and is continued in such closed relation into the bit member 4, and has in the bit member branches as 18, the branches diverging forwardly and having elongated mouths opening into opposite sides of the wing 7, so that the oil is discharged approximately directly at the cutting portion 80 of the drill.

I have already referred to the fact that the bit member 4 has a cylindrical projection 5 driven into the correspondingly shaped socket 6. For additional security the body member and bit member may be keyed together for instance as follows: As shown the forward portion of the body member 3 has projecting keys 19 adapted to fit closely keyways or seats 20 in the bit member. There may be also provided a pin 21 adapted to be driven into registering openings in the body member 3 and bit member 4.

What I claim is:

1. A drill having a plurality of cutting portions, a chip-outlet common to said cutting portions, and a duct extending longitudinally of the drill, having branches leading to the respective cutting portions to convey a lubricant thereto for forcing the chips into said chip-outlet.

2. A drill comprising a shank having a longitudinally extending flute and a wing at approximately right angles to the flute provided with oppositely disposed cutting-edges.

3. A drill comprising a shank having a single flute, and also having a wing at approximately right angles to the entering end of the flute, the wing having oppositely dis-

posed cutting portions and the shank having chip-directing surfaces at the base of the wing leading into said flute.

4. A drill comprising a shank having a flute and a wing, to the base of which said flute leads, said wing having a plurality of cutting portions.

5. A drill comprising a shank having a flute and a wing, to the base of which said flute leads, said wing having a plurality of cutting portions, and its sides being on rearwardly converging angles.

6. A drill comprising a shank having a flute and a wing having cutting portions, the flute extending to the base of the wing, the shank having chip-directing surfaces at

opposite sides of the wing, leading into said flute.

7. A drill comprising a shank having a flute provided with cutting portions, and a wing, the flute extending to the base of the wing, the shank having chip-directing surfaces at opposite sides of the wing, leading into said flute, and also having a longitudinally-extending duct provided with branches opening into the opposite sides of the wing.

In testimony whereof I affix my signature in presence of two witnesses.

BENGT M. W. HANSON.
